UNITED STATES PATENT OFFICE.

ALFONSO MERCER, OF NORFOLK, VIRGINIA.

RIFLE.

1,283,253.

Specification of Letters Patent. Patented Oct. 29, 1918.

Application filed May 3, 1917. Serial No. 166,193.

To all whom it may concern:

Be it known that I, ALFONSO MERCER, a citizen of the United States, residing at Norfolk, in the county of Norfolk and State of Virginia, have invented certain new and useful Improvements in Rifles; and I hereby declare that the following is a full, clear, and exact description thereof, reference being had to the accompanying drawings, which form part of this specification.

This invention is an improvement in rapid-fire rifles especially designed for military use and intended to enable a soldier to fire a number of rounds rapidly and with great precision from the gun while held as an ordinary rifle is held; and the invention includes novel manually operable means controlled by a reciprocatory bar for inserting a cartridge from a holder into the barrel, securely locking it therein, exploding it, and then extracting the shell; a cartridge holder, and means for operating same so as to bring a fresh cartridge into position to be operated on by said means after each firing operation.

The invention has particular reference to the means for operating and locking the breech-bolt so that when the gun is ready to fire the breech bolt will be rigidly locked against retraction; and means whereby the lock can be released and the breech-bolt retracted, the cartridge shell extracted, and the cartridge holder shifted so as to bring a fresh cartridge into position. The invention also includes novel means whereby premature firing of a cartridge is prevented.

I will explain the invention with reference to the embodiment thereof illustrated in the accompanying drawings to enable others to readily understand and utilize the same; and summarize in the claims the novel features and combinations of parts for which protection is desired.

In said drawings:

Figure 1 is a longitudinal section of the gun showing the breech-bolt retracted.

Fig. 2 is a similar view thereof showing the breech-bolt projected and the cartridge inserted just ready to fire.

Fig. 3 is an enlarged transverse section on the line 3-3 Fig. 1.

Fig. 4 is a detail section on line 4-4 Fig. 2.

Figs. 5 and 6 are detail views of the breech-bolt and cartridge shell extracting devices.

Referring to the drawings, 1 designates the breech casing or frame in and on which the main operative parts are mounted; the barrel 1^a is attached to one end of this casing, and a stock 1^b of any suitable construction may be attached to the other end thereof, so that the gun externally resembles an ordinary rifle.

Slidably mounted within the casing 1, in axial alinement with the barrel 1^a, is a breech-bolt 2 which is adapted to be moved toward and from the barrel 1^a a distance slightly greater than the length of a regulation cartridge to be used with the gun.

This breech-bolt is guided in a suitable bore in the casing 1 and has no radial or lateral movement, and it is provided on its under side with a depending lug 2^a to which is pivoted a locking abutment 3; which may be connected thereto by a pin 3^a; but the end of the abutment 3 adjacent the pivot is preferably rounded and fitted in a circular shoulder 2^b within the lug 2^a so as to relieve the pivot 3^a of strain.

The free end of the locking abutment 3 is also preferably rounded as at 3^b to engage a correspondingly rounded surface of a fixed abutment 1^c formed within the casing 1.

At the top and in rear of this abutment 1^c is a guide 1^d upon which the abutment 3 may rest as indicated in Fig. 1 when the abutment is raised and the breech-bolt retracted.

The locking abutment 3 is provided with a depending finger 3^e that projects at an angle to the abutment 3, and preferably has a slot 90 and pin engagement, indicated at 3^a, with a sliding bar 4 which is suitably guided in the casing 1 and is suitably connected with exterior hand pieces 4^a and 4^b by which it can be manually reciprocated by the hand of the operator, the casing being slotted as shown at 1^e to permit the reciprocatory movements of the bar and hand pieces.

When bar 4 is pulled inward the abutment 3 will be first thrown upward by reason of 100 the engagement of the bar with arm 3^e so that the locking abutment 3 will clear the abutment 1^c, and then the bar 4, abutment 3 and breech-bolt 2 can all be moved backward from the position shown in Fig. 2 to 105 the position shown in Fig. 1; and thus fully retract the breech-bolt, as shown in Fig. 1.

When the parts are in the position shown in Fig. 1, if the bar is moved outward the breech-bolt 2 is projected toward the barrel 110

and the abutment 3 slides on the guide 1^d until it reaches the abutment 1^e and then engages therewith as indicated in Fig. 2, firmly locking the breech bolt in its projected position.

If the cartridge C has been inserted in the barrel 1^a while the breech-bolt was retracted it would be firmly held in the barrel by the breech-bolt, when the latter is projected into the position shown in Fig. 2, and the cartridge may then be safely exploded, as hereinafter described.

The cartridges are preferably automatically fed between the breech-bolt, when retracted, and the barrel 1^a by any suitable means.

Preferably I employ an annular holder 5 which can be slipped over the barrel and end of the casing 1 into the position shown in Fig. 1, and said ring can be supported and guided on a support 1^e formed on or attached to the casing 1.

The holder carries an annular series of clips 5^a each of which is adapted to hold a cartridge C in such manner that the cartridge can be moved endwise from a clip into the barrel. The particular construction of these clips is not a feature of the present invention; but each clip should be so formed as to hold a cartridge in proper position, and yet permit it to be moved endwise therethrough by the breech-bolt.

Means should be provided for automatically rotatively shifting the holder 5 each time that a cartridge is fired so that when the breech-bolt is retracted after the firing of a cartridge the holder 5 will be moved sufficiently to bring a fresh cartridge into position between the breech-bolt and the barrel.

In the drawings the holder 5 is shown as provided with notches 5^c on its under side, one for each clip 5^a, and these notches are adapted to be engaged by a spring-actuated pawl 6^a pivotally mounted on an arm 6 fulcrumed on a pin 6^b attached to a lug 1^f in the casing or bearing 1^e (see Fig. 3); this lever 6 may be normally retracted by a spring 6^c as shown; and the part 6^d of said lever is adapted to engage with a cam 4^e on the upper side of the sliding bar 4; said cam being so formed and located that at the proper time during the return movement of the bar 4 the lever 6 will be rocked to impart sufficient rotatorial movement to the cartridge holder 5 to move an empty clip 5 out of the way of the breech-bolt and bring a fresh cartridge into position between the breech-bolt and the barrel 1^a.

When bar 4 is moved inward the lever 6 will be moved upward by cam 4^e, and the pawl 6^a will engage a notch 5^c and move the holder one notch or step. The holder may be prevented from turning backward by means of a pawl 6^d (see Fig. 3) pivoted on a

lug 6^b and held in operative position by a spring 6^e. When the bar 4 is moved outward spring 6^c retracts the lever 6 and pawl 6^a so that upon the next inward movement of the bar 4 the holder will be moved another step. Any suitable means may be provided for imparting the necessary movement to the holder; and while I prefer to use a ring-shaped holder, I do not consider the invention restricted to the employment of such a ring-shaped holder.

The cartridge holder is not shifted until after the breech-bolt has been retracted clear of the holder and just before it reaches the position shown in Fig. 1, and it is shifted before the breech-bolt is projected, so that as the breech-bolt is projected its forward end engages the shouldered end of the cartridge and pushes same from and through the clip into the barrel 1^a; in this movement the breech-bolt passes through the clip.

On the outer end of the breech-bolt 2 is a lower lip 2^b which is adapted to engage under the rim of the cartridge C, see Fig. 5, and partially support the same. Attached to the breech-bolt opposite the lip 2^b is an extractor finger or spring 2ⁱ having a hook 2^j on its free end opposite the lip 2^b, which hook will engage over the upper end of the rim of the cartridge and clamp the rim against the lip 2^b so that when the breech-bolt is retracted, (see Figs. 1, 5 and 6) the extractor hook 2^j will withdraw the exploded cartridge shell from the barrel breech.

When the cartridge shell has been extracted from the barrel, it may, if desired, be knocked out of the way by any suitable means, (not shown) but as shown the extractor finger 2ⁱ is provided with a lug 2ⁿ near its free end, which lug is adapted to engage a beveled slot 2° in the top of the casing adjacent the breech-bolt, and when the breech-bolt moves inwardly the free end of extractor 2ⁱ is raised so as to release the empty shell and leave it in the clip from which it was removed.

The breech-bolt 2 is bored for the passage of a firing pin 7, the stem 7^a of which extends outwardly through an opening in the end wall of the casing 1. Said firing pin is normally forcibly projected inward by means of a spring 7^b interposed between a collar 7^c on the stem and the end wall of the casing 1. The collar 7^c is adapted to abut against the inner end of the breech-bolt and arrest the forward movement of the firing pin after it has exploded the cartridge.

When the breech-bolt is moved backward it engages collar 7^c and moves the firing pin 125 also backward, tensioning spring 7^b, until the lug 7^e on the collar engages a spring-actuated catch lever 8, pivoted at 8^d within the casing 1. The long arm 8^b of the catch 8 is adapted to be engaged by a finger 9^b on 130

a trigger 9, which is pivoted at 9^a in the casing, and projects so that it can be operated by the finger in the usual manner, said trigger being protected by the usual finger-guard 9^d.

To the finger 9^b may be attached a pin 9^c which, when the breech-block is retracted, lies over a rearward extension 4^e of the slide 4 and is upheld thereby so that when in such position a pull on the trigger cannot release the catch 8. This extension 4^e is of such length that it does not clear the pin 9^c until just as or after the breech-bolt has seated the cartridge in the barrel and the locking abutment has locked the breech-block in position; so the trigger cannot be pulled before the breech-block is securely seated and locked ready for firing.

It will be seen that upon the inward or rearward movement of the breech-block 2 as described the firing pin is cocked and locked by the catch 8, putting spring 7^b under tension and just after the breech block has securely pressed a cartridge into the barrel as indicated in Fig. 2 the extension 4^e of the slide disengages pin 9^c and then by a pull on the trigger the firing pin may be released, whereupon the spring 7^b will drive the firing pin outward and explode the cartridge.

Operation.

When it is desired to use the rifle the proper holder is positioned thereon, while the breech-bolt is retracted to the position shown in Fig. 1, so that a cartridge in a clip on the holder will be positioned between the end of the breech-bolt and the barrel; then, when it is desired to fire the rifle, the bar 4 and the breech-bolt are projected forwardly by pulling the hand piece 4^a or 4^b outwardly; in its outward movement the breech-bolt engages the butt of the cartridge and slides it endwise through the clip on the holder into the barrel 1^a to the position shown in Fig. 2; leaving the firing pin 7 cocked in the position shown in Fig. 2. The rim of the cartridge is engaged between the finger 2^h and the hook 2ⁱ of the extractor. When the breech-bolt has securely seated the cartridge in the barrel it can be exploded by pulling the trigger 9, which is then freed from the control bar 4^e.

Upon the return movement of the bar 4 and breech-bolt the cartridge shell is extracted from the barrel by the hook 2ⁱ and in the example shown is drawn back into the same clip from which the cartridge was taken; but as or before the shell is pulled back to its original position in the clip the lug 2ⁿ on the extractor engages bevel 2° and causes the hook to disengage the shell which is then retained in the clip. Just after the hook and breech-bolt clear the clip the cam 6^c on bar 4 engages lever 6 and imparts a

sufficient movement to the cartridge holder to carry the clip containing the empty shell out of the way and bring another clip containing a fresh cartridge into position between the breech-bolt and the barrel so that on the next outward movement of the breech-bolt another cartridge will be inserted in the barrel, and may be fired as desired.

While a rotary cartridge holder is shown any suitable form of cartridge holder might be used in connection with my rifle. When the breech-bolt is fully projected, as shown in Fig. 2, the abutment 3 engaging the fixed abutment 1^c forms a positive lock and solid bearing between the breech-bolt and the casing or stock so that the breech-bolt is securely held and the shock is transmitted practically solidly through the breech-bolt to the casing 1.

The abutments 3 and 1^c may be so shaped that they will practically wedge on the outward pull or movement of the bar 4; and on the inward movement of the bar 4 the abutment 3 will be raised clear of the abutment 1^c so that the breech-bolt can be retracted. The extension 4^e of the bar 4 forms a safety device to prevent a pull on the trigger releasing the firing pin prematurely.

If the cartridge holder is removed a single cartridge can be inserted in the barrel by hand and locked therein by the forward movement of the breech-bolt, and fired in the manner described.

From the foregoing description and the drawings those familiar with the art can readily adapt and use the invention, and modify specific features thereof according to the size or character of cartridges to be employed within the scope of the invention while retaining the essential features thereof. While the invention is shown as embodied in a rifle to be carried by an individual in place of the ordinary rifle, it could be readily adapted for larger guns by properly proportioning and modifying the parts to suit the heavier projectiles employed. If desired the barrel could be removable and interchangeable in the well known manner so that in case it should become over-heated another barrel might be easily substituted therefor.

What I claim is:

1. In a gun the combination of a barrel, a slidable breech-bolt, a movable abutment pivoted to the breech-bolt and having a depending arm; a guide below and parallel with the breech-bolt adapted to slidably support the movable abutment, a fixed abutment at the forward end of the guide adapted to be engaged by the movable abutment when the breech-bolt is projected, and a reciprocatory bar connected with the arm on said movable abutment; with a cartridge carrier mounted between the retracted breech bolt and the barrel; a pawl and lever for shifting

said carrier so as to successively present the cartridges in position for insertion by the breech-bolt into the barrel, a cam on said bar for operating said pawl and lever, and means for retracting an empty shell from the barrel when the breech-bolt is retracted.

2. In a gun the combination of a casing, a barrel connected therewith, a breech-bolt slidably mounted in said casing, a movable abutment pivoted to the breech-bolt and having a depending arm, a slotted guide for the said abutment below the breech-bolt, a fixed abutment at the front end of said guide adapted to be engaged by the movable abutment, a reciprocatory bar connected with the arm on said movable abutment, said arm moving in the slot of the guide; means for feeding cartridges between the retracted breech-bolt and the barrel, a firing pin, a trigger for releasing said pin, and means connected with the reciprocatory bar engaging the trigger when the bar is retracted for

preventing premature release of the firing pin.

3. In a gun the combination of a barrel, a 25
slidable breech-bolt, a movable abutment connected with the breech-bolt, a fixed abutment adapted to be engaged by the movable abutment when the breech-bolt is projected, a reciprocatory bar connected with the said 30
movable abutment; means for feeding cartridges between the retracted breech-bolt and the barrel; a firing pin in the breech-bolt, a spring for projecting the firing pin, means for locking the firing pin in cocked position 35
when the breech-bolt is projected, a trigger for releasing the firing pin, and a rearwardly extending finger on the sliding bar engaging said trigger when the bar is retracted for preventing premature release of 40
the firing pin.

In testimony that I claim the foregoing as my own I affix my signature.

ALFONSO MERCER.
